FINISHING MACHINE

Irving E. Booth, Rochester, N. Y., assignor to
United Shoe Machinery Corporation, Paterson,
N. J., a corporation of New Jersey

Application November 11, 1929, Serial No. 406,350

16 Claims.

This invention relates to shoe finishing machines and is illustrated as embodied in a machine of the type used for burnishing or setting sole edges.

It is customary in machines of this type having burnishing tools which are rapidly oscillated to provide a self-aligning mounting for each tool whereby it may rotate slightly to either side of a normal position, in accordance with changes in the contour of the sole edge of the shoe being operated upon. In such machines the edge treating tools are commonly releasably secured to a carrier arranged to yield in the head of the machine to facilitate burnishing the sole edge evenly on all parts of the sole. To allow the rotative movement of the tools referred to above, they have ordinarily been mounted for limited rotation on the end of the carrier which is usually mounted for yielding axial movement in the machine head. One embodiment of such a burnishing tool mounting is shown and described in Letters Patent of the United States No. 1,841,647, granted January 19, 1932, on an application filed in the name of A. C. Smith.

An object of the present invention is to provide an improved mounting for an edge burnishing tool allowing a limited rotation of the burnishing tool as well as yielding axial movement. In accordance with this object of the invention one of its novel features consists in the combination with a yielding tool carrier mounted for limited rotation in a holder in the head of a machine of the type referred to, of means on one end of the carrier for holding an edge burnishing tool in non-turning relation thereon. Although the tool carrier may be mounted in the head of the machine for limited rotation in any suitable manner, the illustrated carrier is mounted in substantially the same manner as that disclosed in copending application Serial No. 406,133, filed on November 9, 1929, in the name of William Hamann.

It will be apparent that as a result of the above construction the fit between the tool and the carrier may be relatively tight, thereby to reduce to a minimum the wear between the tool and the carrier owing to the rapid vibration of the tool, the yielding joint which allows limited rotation of the tool being between the carrier and the holder where large bearing surfaces may be provided without making any sacrifices in the design of the machine.

The means illustrated herein for holding an edge treating tool in non-turning relation on the carrier is constructed and arranged releasably to

hold the tool in alignment with the carrier, and to allow the tool to rotate transversely of the carrier, the carrier being mounted in the head of the machine to yield in accordance with the contour of the sole edge of the shoe being treated.

It is an object of the present invention to provide a device for holding an edge treating tool in non-turning relation on the carrier, and to allow the tool to rotate transversely of the carrier.

It is another object of the present invention to provide a device for holding an edge treating tool in non-turning relation on the carrier, and to allow the tool to rotate transversely of the carrier.

It is a further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

It is a still further object of the present invention to provide a device for holding an edge treating tool in non-turning relation on the carrier, and to allow the tool to rotate transversely of the carrier.

a resiliently operated latch 24 which is pivoted on a fulcrum screw 26 supported by lugs 28 extending from the carrier 10. A spring 30 seated in a recess in the carrier is arranged to urge the latch about the fulcrum screw 26 to hold the rounded toe portion 32 of the latch in the notch 20 of the tool on the carrier. By the above means the edge burnishing tools are releasably secured to the carrier.

10 In order to secure the type of tool illustrated in Fig. 2 to the carrier in non-turning relation, shoulders 34 are fixed to and arranged to extend from the carrier 10 and to embrace opposite flat sides of this tool, as illustrated in Fig. 3, 15 thereby positively resisting rotation of the tool on the carrier.

It is apparent that the shoulders 34 will be ineffective to prevent a tool such as disclosed in Figs. 4 and 5 having a shank which is substantially circular in cross-section from rotating on the carrier. However, in order effectively to resist rotation of such a tool on the illustrated carrier, a heel portion 36 having a plane face on the latch 24 in proximity to the fulcrum is arranged to bear on the flat 22 of the shank of the tool 18. Owing to the relatively short moment arm between the heel portion 36 and the fulcrum screw 26, a relatively strong spring 30 will render the latch effective to resist rotation 25 between the tool 18 and the carrier 10; but the desired rotation is allowed to occur between the carrier 10 and the holder, as described in the above-mentioned Hamann application.

The illustrated carrier 10 is urged outwardly 30 of a tool holder 38, which, like the holder in the Hamann machine referred to above, is mounted to oscillate on a hollow shaft 39, by means of a spring 40 one end of which bears on the tool holder and the other end being seated at the bottom of a recess in the carrier. To allow a limited and yieldingly resisted rotative movement of the carrier 10 with respect to the holder 38, the carrier has associated therewith a key 42 (Figs. 6 and 7) arranged to engage a flat 44 35 on the carrier and which is yieldingly held in engagement therewith by means of a spring 46. The key 42 also is restrained from all movement except that in a plane perpendicular to the axis of the carrier in the key holder 48. It will now be apparent, from a consideration 40 of Figs. 6 and 7, that when the carrier is rotated with respect to the holder a corner of the flat 44 will engage the key 42, rotating it in its holder 38 about its end farthest removed from 45 the point of contact of the carrier and the key; and when the back of the key reaches the adjacent wall of the key holder its movement is positively limited. As indicated in Fig. 6, shoulders 50, 52 of the recess in the carrier, of which the flat 44 is the base, are separated by a distance substantially greater than the width of the key 42. Before any work is presented to the tool the spring 40 urges the carrier 10 outwardly of the holder 38 so that the shoulder 52 on the carrier 55 abuts the adjacent side of the key 42. In this manner outward displacement of the tool is limited. Similarly, when a piece of work is held against the tool to urge the carrier inwardly of the holder, this movement of the carrier is positively limited when the shoulder 50 on the carrier engages the key 42. It will now be apparent 60 that the same means, namely the key device above described, is constructed and arranged 65 to limit both axial and rotative move-

ments of the carrier as well as yieldingly to resist rotative movement of the carrier.

Having thus described my invention, what I claim as new and desire to secure by Letters Patent of the United States is:

1. In a finishing machine, the combination of a tool carrier mounted normally to have axial and rotative movement, and means on one end of said carrier for holding an edge treating tool in non-turning relation thereon. 10

2. In a finishing machine having a tool holder, the combination of a tool carrier mounted normally to have axial and rotative movement of limited extent in said holder while finishing the work, and means on one end of said carrier for 15 releasably securing an edge treating tool in non-turning relation thereto.

3. In a finishing machine, the combination of a tool carrier mounted normally to have axial and rotative movement, and means on the end 20 of said carrier for releasably retaining an edge treating tool thereon and for positively resisting any rotation of said tool on said carrier.

4. In a finishing machine, the combination of a tool carrier mounted normally to yield axially 25 and to rotate, and means on said carrier for releasably retaining an edge treating tool thereon constructed and arranged also to resist rotation of said tool on said carrier.

5. In a finishing machine having a tool holder, 30 the combination of a tool carrier mounted to rotate in said holder, and means for releasably retaining a tool on said carrier comprising a pivoted latch constructed and arranged also to resist rotation of said tool on said carrier. 35

6. In a finishing machine having a tool holder, the combination of a tool carrier mounted normally to rotate in said holder, and means on said carrier for releasably holding an edge treating tool thereon, said carrier being constructed and 40 arranged to cooperate with the tool to prevent any relative rotation thereof. 40

7. In a finishing machine having a tool holder, the combination of a tool carrier mounted to rotate yieldingly in said holder, and means for 45 releasably retaining an edge treating tool on the end of said carrier comprising a latch constructed and arranged also to prevent relative rotation of the tool and said carrier. 45

8. In a finishing machine having a tool holder, 50 the combination of a tool carrier mounted yieldingly to rotate in said holder, and means on the end of said carrier for releasably securing a tool thereto comprising a pivoted latch, said end of the carrier being constructed and arranged to embrace the sides of said tool thereby to prevent 55 relative rotation between the carrier and the tool.

9. In a finishing machine, a tool carrier, and a pivoted latch for releasably securing an edge 60 treating tool on said carrier constructed and arranged to engage a flat on the tool in proximity to the fulcrum of the latch thereby effectively to resist relative rotation between the tool and the carrier and to engage a notch in the tool 65 to resist removal of the tool from the carrier.

10. In a finishing machine having a tool holder, the combination of a tool carrier mounted yieldingly to rotate in said holder, and a latch on the end of said carrier for releasably securing a 70 tool thereto, said end of the carrier having lateral extensions arranged to engage opposite sides of the tool thereby to prevent relative rotation between the carrier and the tool. 70

11. In a finishing machine having a tool holder, 75

- a tool carrier rotatably mounted in said holder, and a pivoted latch for releasably securing an edge treating tool on said carrier constructed and arranged to engage a flat on the tool in 5 proximity to the fulcrum of the latch thereby effectively to resist relative rotation between the tool and the carrier.
12. In a finishing machine, a tool carrier, and a pivoted latch for releasably securing an edge 10 treating tool on said carrier, said latch having a rounded toe portion arranged to engage a notch in said tool to resist axial displacement thereof on the carrier and having a plane heel portion in proximity to the fulcrum thereof arranged to engage a flat on the tool thereby 15 effectively to resist relative rotation between the tool and the carrier.
13. In a finishing machine having a tool holder, the combination of a tool carrier mounted to 20 rotate in said holder, means for yieldingly resisting the rotation of said carrier, said carrier having a projecting pin, an edge treating tool mounted on said pin, and connections between said carrier and tool for releasably securing the tool to the 25 pin in non-turning relation.
14. In a finishing machine having a tool holder, the combination of a tool carrier mounted yieldingly to rotate in said holder, said carrier having a projecting pin, an edge treating tool mounted on said pin, and connections between the tool and the carrier for releasably securing the tool on the pin and for positively preventing any relative rotation therebetween. 5
15. In a finishing machine, a tool carrier having a projecting pin, an edge treating tool mounted 10 on said pin, a pivoted latch arranged to engage a notch in said tool to resist removal of the tool from the pin, and shoulders on the carrier and cooperating with said pin to prevent relative rotation between the tool and the carrier. 15
16. In a finishing machine, a tool carrier having a projecting pin, and a pivoted latch for releasably securing an edge treating tool on said pin, said latch being constructed and arranged to engage a notch in the central portion of said 20 tool and a flat on one end of said tool in proximity to the fulcrum of the latch thereby to hold the tool on the pin in non-turning relation thereto.

IRVING E. BOOTH. 25
